UNITED STATES PATENT OFFICE.

ANGUS DARROCH, OF NEW YORK, N. Y.

GRATING.

1,150,746.

Specification of Letters Patent. Patented Aug. 17, 1915.

Application filed September 5, 1914. Serial No. 860,479.

To all whom it may concern:

Be it known that I, ANGUS DARROCH, a citizen of the United States, and a resident of the city of New York, borough of Brooklyn, in the county of Kings and State of New York, have invented a new and Improved Grating, of which the following is a full, clear, and exact description.

The invention relates to gratings, such as shown and described in the Letters Patent of the United States, No. 1,092,094, granted to me on March 31, 1914.

The object of the invention is to provide a new and improved grating for use in the roofs of subways, pavements, buildings and other structures, and arranged to prevent rain water, debris and the like from passing through the grating, to illuminate the space below the grating by refracting light and to provide proper ventilation for the said space.

In order to accomplish the desired result, use is made of spaced grate bars and diaphanous gutters intermediate the said grate bars and arranged below the same to carry off water and to refract light into the space below the grating, the side edges of each gutter extending underneath adjacent grate bars and being spaced therefrom to form ventilating spaces.

A practical embodiment of the invention is represented in the accompanying drawings forming a part of this specification, in which similar characters of reference indicate corresponding parts in all the views.

Figure 1 is a sectional perspective view of the grating; Fig. 2 is a longitudinal section of the grating; Fig. 3 is a transverse section of the same; and Fig. 4 is a perspective view of one end of one of the grate bars.

In order to form the grating, use is made of a series of grate bars A of iron or other suitable material and provided at the under side of their ends with depending lugs A' adapted to rest on the flat faces B' of side supports B mounted on top of walls C of a subway, building or other structure and having a space below the grating. The grate bars A are spaced apart and reversible and both faces of the grate bars are preferably grooved in a transverse direction so as to provide the desired foothold for people walking over the grating. Bolts A² pass through the ends of each grate bar A and through the lugs A' thereof to screw into the side supports B with a view to securely fasten the grate bars A in place. Gutters

D of glass or other diaphanous material are arranged intermediate adjacent grate bars A and are disposed below the same, and each end of a grate bar D fits into a correspondingly shaped recess B² formed in a corresponding side support B, it being understood that the gutters D are preferably V-shape in cross section, as plainly indicated in the drawings. The side edges of each gutter D extend beneath the under side of adjacent grate bars A and are spaced therefrom so as to form ventilating spaces for the escape of foul air from the space below the grating. It will also be noticed that any rain water will readily drip off the side edges of a grate bar into the adjacent gutters D, and as the latter are made of diaphanous material they readily refract light into the space below the grating. The curb E of a street abuts against the outermost side support B and its top is flush with the top faces of the side bars A, and the said abutment E is provided with cut-out portions E' registering with the gutters D so that the rain water in passing into the gutters D can pass through the cut-out portions E' into the gutter E² of the street to be carried off to a suitable place of discharge. It will be noticed that by the arrangement described a sufficient tread is provided by the grate bars A for persons to walk on and at the same time the diaphanous gutters D are protected from injury by persons walking over the grating.

In case of very heavy rains the gutters D may be unable temporarily to carry off all the rain water, and in order to prevent the overflow water of the gutters from dropping down into the space below the grating, use is made of auxiliary or overflow gutters F of glass or similar diaphanous material and arranged below the main gutters D. The overflow gutters F are likewise V-shaped in cross section and are spaced from the under sides of the main gutters D and supported from the same by suitable clamps G, as plainly indicated in Figs. 1, 2 and 3. The ends of the overflow gutters F abut against the inner faces of the side supports B. Each overflow gutter F is provided preferably at one end with drain pipes H for carrying off the overflow water to a suitable place of discharge.

By providing the side supports B with the flat faces B' alternating with the recesses B² the main gutters D can be readily placed

in position on the said side supports B and then the grate bars A can be fastened in place on the side supports. The side edges of the lugs A' are beveled to correspond to 5 the edges of the main gutters D thereby holding the latter securely locked in place when fastening the grate bars A in position on the side supports B.

It will be noticed that by the arrangement 10 described the several parts can be readily assembled and a desired tread is provided for persons to walk on and at the same time refracted light can pass into the space below the grating and foul air can pass from 15 the said space into the outer air.

Having thus described my invention, I claim as new and desire to secure by Letters Patent:

1. A grating, comprising spaced grate 20 bars and diaphanous main gutters intermediate the said grate bars and below the same to carry off rain water and to refract light into the space below the grating, the side edges of each gutter being spaced from adjacent grate bars to form ventilating spaces.

2. A grating, comprising spaced grate 30 bars and diaphanous main gutters intermediate the said grate bars and below the same to carry off rain water and to refract light into the space below the grating, the side edges of each gutter extending underneath adjacent grate bars and being spaced from the under side thereof to form ventilating spaces.

3. A grating, comprising spaced grate 35 bars, diaphanous main gutters intermediate the said grate bars and below the same to carry off rain water and to refract light into the space below the grating, the side edges of each gutter being spaced from adjacent grate bars to form ventilating spaces, and an overflow gutter of diaphanous material and extending under each main gutter and being spaced therefrom.

4. A grating, comprising spaced grate 45 bars, diaphanous main gutters intermediate the said grate bars and below the same to carry off rain water and to refract light into the space below the grating, the side edges of each gutter being spaced from ad-

jacent grate bars to form ventilating spaces, an overflow gutter of diaphanous material and extending under each main gutter and being spaced therefrom, and a drain pipe connected with the said overflow gutter for 55 carrying off overflow water.

5. A grating, comprising side supports, transversely extending spaced grate bars secured at their ends to the said side supports, and main gutters intermediate adjacent 60 grate bars and supported at their ends on the said side supports independent of the said grate bars, the side edges of each gutter being spaced from the under sides of adjacent grate bars throughout their lengths to 65 form ventilating spaces.

6. A grating, comprising side supports, transversely extending spaced grate bars secured at their ends to the said side supports, main gutters intermediate adjacent 70 grate bars and supported at their ends on the said side supports, the side edges of each gutter being spaced from the under sides of adjacent grate bars to form ventilating spaces, overflow gutters underneath 75 the said main gutters and parallel thereto, means for fastening the said overflow gutters to the said main gutters, and means for draining the said overflow gutters.

7. A grating, comprising side supports, 80 transversely extending spaced grate bars secured at their ends to the said side supports, main gutters intermediate adjacent grate bars and supported at their ends on the said side supports, the side edges of each gutter 85 being spaced from the under sides of adjacent grate bars to form, ventilating spaces, and an abutment on the outer face of a side support and having its top flush with the top faces of the said grate bars, the said 90 abutment having cut-out portions registering with the said main gutters to carry off the water.

In testimony whereof I have signed my name to this specification in the presence of 95 two subscribing witnesses.

ANGUS DARROCH.
